UNITED STATES PATENT OFFICE

2,670,592

TIMEPIECE WINDING INDICATOR

Herbert Jeanneret, Geneva, Switzerland

Application March 6, 1951, Serial No. 214,045

Claims priority, application Switzerland
April 19, 1950

2 Claims. (Cl. 58—85)

1

This invention relates to a timepiece comprising a device indicating the unwinding of the spring. This timepiece comprises a wheel provided with two sets of teeth, one meshing with an intermediate wheel the shaft of which is fixed and the other with a satellite pinion of which the carrier drives the indicator member, the said intermediate wheel being driven by one of two elements, that is to say either by the barrel or by the barrel arbor, while the pinion is driven by the other of the said two elements.

The accompanying drawings illustrate two embodiments of the invention by way of example.

Fig. 1 is a plan view of a first embodiment of the device.

Fig. 2 is a section on line II—II of Fig. 1.

Fig. 3 is a plan view of a second embodiment of the device and,

Fig. 4 is a section on line IV—IV of Fig. 3, on a larger scale.

The timepiece illustrated in Figs. 1 and 2 comprises a plate 1 to which is fixed, on the side nearest the dial designated by 2, a supplementary bridge 3 in which is pivoted one extremity of the barrel arbor designated by 4. The barrel itself is indicated by 5. It is rigid with a sleeve 6 passing freely through the plate and bearing against the arbor 4. Carried by this arbor and keyed to it is a pinion 7, while the sleeve 6 carries a pinion 8. A wheel 9 is freely mounted on the arbor 4 between the pinions 7 and 8; this wheel 9 is pivoted with internal teeth 10 on its upper face and internal teeth 11 on its lower face.

The teeth 11 mesh with an intermediate wheel 12 of which the shaft 13 is fixed to the plate; this intermediate wheel is itself driven by the pinion 8, while the teeth 10 mesh with a satellite 14 which itself meshes with the pinion 7. This satellite is carried by a wheel 15 freely mounted on the arbor 4. This wheel 15 drives a wheel 16 pivoted in the centre of the movement and carrying an annular disc 17 which constitutes the member indicating unwinding and on the upper face of which are inscribed the indications which appear through a window 18 made in the dial 2. It is to be noted that one sector 19 (Fig. 1) of the wheel 16 has no teeth. On the side opposite this sector the wheel 16 carries a pin 20 in the path of which is situated a blade spring 21 fixed to the framework at 22 by one of its extremities and extending radially in relation to the wheel 16.

The operation of this device is as follows:

When the movement is being wound up, the pinion 7 turns the satellite 14 which, meshing with the teeth 10 of the wheel 9, brings about the

2

rotation of the wheel 15 which rotation is transmitted to the wheel 16. When the spring is fully wound, the part 19 of the wheel 16 arrives opposite the wheel 15; the winding members can thus continue to function, for instance under the action of an automatic winding means, without turning the wheel 19. It is to be noted that as soon as the wheel 15 turns in the opposite direction it is again in engagement with the toothed portion of the wheel 16 because of the action of the spring 21 which acts as a return spring. This backward rotation of the wheel 15 will be produced by the barrel through the intermediary of the pinion 8, the intermediate wheel 12, the wheel 9 and the satellite 14.

The timepiece illustrated in Figs. 3 and 4 comprises a plate 23 on the lower face of which is arranged a barrel 24 of which the cover 25 carries a pinion 26 rigid with said cover. A cavity 27 is made in the lower face of the plate, while a cavity 28 is made in its upper face. These two cavities are in communication with one another. An intermediate wheel 29 is arranged in the cavity 27 while an intermediate wheel 30 is arranged in the cavity 28, each of these intermediate wheels being pivoted on journals made unitary with the plate. These two intermediate wheels mesh with one another over a part of their height; in addition, the intermediate wheel 29 meshes with the pinion 26, while the intermediate wheel 30 meshes with external teeth 31 of a wheel 32, with two sets of teeth, which is rotatably mounted on the barrel arbor 33 and is situated on the upper face of the plate. The wheel 32 is provided with internal teeth 34 in which meshes a satellite pinion 35 carried by a rotary carrier 36 which is freely mounted on the shaft 33. This carrier is provided with teeth 37 meshing with a wheel 38 pivoted in the centre of the movement and carrying an annular dial 39 on which are inscribed indications 40 indicating the unwinding of the spring and appearing through a window 41 made in the dial 42. The vertical play of the carrier 36 is limited by an annular bridge 43 serving as an abutment for a disc 44 riveted to the carrier 36 of the satellite pinion. This pinion is driven by a pinion 45 keyed to the barrel arbor 33.

The operation of the device is as follows:

When the timepiece is being wound up, action is being produced on the barrel arbor, which drives the satellite 35 by the pinion 45, whereby the carrier 36 is caused to turn; this carrier turns the wheel 38 carrying the unwinding indicator. When the movement is running, the barrel by turning drives the wheel 32, which is provided

with two sets of teeth, through the intermediary of the pinion 26 and the intermediate wheels 29 and 30.

The wheel 32 itself through the intermediary of the satellite 35 turns the carrier 36 which drives the wheel 38. The various gears are arranged in such a way that when the movement is being wound up the wheel 38 turns in the opposite direction to that in which it turns when the movement is running.

What I claim is:

1. In a timepiece comprising a device indicating the unwinding of the main spring, a base-plate provided with two cavities each on one of its faces and communicating with one another, a barrel situated below said base-plate, a pinion rigid with said barrel, a barrel arbor, a wheel situated above said base-plate and provided with two sets of teeth, two intermediate wheels pivoted each in one of said cavities and meshing with one another, one of said intermediate wheels meshing with one of said two sets of teeth and the other with said pinion rigid with the barrel, so that the wheel with two sets of teeth, situated above the base-plate, is driven by the barrel situated below the base-plate, a satellite pinion meshing with the other of said sets of teeth, a pinion rigid with the barrel arbor and meshing with said satellite pinion, a toothed carrier carrying said satellite pinion, a wheel meshing with said toothed carrier, and an indicator member carried by said last mentioned wheel indicating the unwinding of the main spring.

2. In a timepiece comprising a device indicating the unwinding of the main spring, a base-plate provided with two cavities, each on one of its faces and communicating with one another, a barrel situated below said base-plate, a pinion rigid with said barrel, a barrel arbor, a wheel situated above said base-plate and provided with two sets of teeth, one external and the other internal, two intermediate wheels pivoted each in one of said cavities and meshing with one another, one of said intermediate wheels meshing with said set of external teeth and the other with said pinion rigid with the barrel, so that the wheel with two sets of teeth, situated above the base-plate, is driven by the barrel situated below the base-plate, a satellite pinion meshing with said set of internal teeth, a pinion rigid with the barrel arbor and meshing with said satellite pinion, a toothed carrier carrying said satellite pinion, a wheel meshing with said toothed carrier, and an indicator member carried by said last mentioned wheel indicating the unwinding of the main spring.

HERBERT JEANNERET.
